UNITED STATES PATENT OFFICE

157,792

AUTOMOBILE ACCESSORY DISPLAY FIXTURE

Harry J. Roberts, University Heights, Ohio, assignor to Roberts Designs, Inc., Cleveland, Ohio

Application May 27, 1947, Serial No. 139,297

Term of patent 14 years

(Cl. 80—11)

To all whom it may concern:

Be it known that I, Harry J. Roberts, a citizen of the United States, residing in the city of University Heights, county of Cuyahoga, and State of Ohio, have invented a new, original, and ornamental Design for an Automobile Accessory Display Fixture, of which the following is a specification, reference being had to the accompanying drawings, forming a part thereof:

Figure 1 is a perspective view of an automobile accessory display fixture, showing my new design; and

Figure 2 is a perspective view of individual parts in unassembled relation.

The back of the display fixture is substantially plain.

I claim:

The ornamental design for an automobile accessory display fixture, substantially as shown, and described.

HARRY J. ROBERTS.
